UNITED STATES PATENT OFFICE.

FREDERICK DANIEL GROSS, OF DENVER, COLORADO, ASSIGNOR OF ONE-HALF TO COLORADO IRON WORKS COMPANY, OF DENVER, COLORADO.

TAP-SPOUT FOR SMELTING-FURNACES.

No. 910,371.

Specification of Letters Patent.

Patented Jan. 19, 1909.

Application filed July 11, 1906. Serial No. 325,735.

To all whom it may concern:

Be it known that I, FREDERICK DANIEL GROSS, a citizen of the United States, residing in the city and county of Denver and State of Colorado, have invented certain new and useful Improvements in Tap-Spouts for Smelting-Furnaces; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in tap spouts for smelting furnaces.

The tap spout is the device through which the molten material from the smelting furnace passes from the furnace to the settler or the receptacle where the final separation of the slag from the matte is effected. Heretofore so far as I am aware these spouts have been made entirely of copper since copper is apparently the only material that will resist the wearing or destructive action of the matte on the tip for any considerable length of time. The objection to the copper tap spout is that when the tip becomes worn the entire spout must be removed and a new one substituted.

In my improved construction I make the tip of the spout removable whereby when it becomes worn the tip may be removed and a new one substituted, and as the tip constitutes but a small part of the spout, this construction is exceedingly advantageous over the original construction. Moreover in my improved construction the body of the spout consists of an outer shell of cast iron provided with a lining of refractory brick or brick adapted to long resist the action of the matte. I have found magnesic brick best adapted for this purpose though the invention is not limited to this particular material.

Having briefly outlined my improved construction, I will proceed to describe the same in detail, reference being made to the accompanying drawing in which,

Figure 1 is a vertical longitudinal section of my improved tap spout taken on the line 1—1 Fig. 2. Fig. 2 is a top plan view of the tap spout. Fig. 3 is a front end elevation of the same.

The same reference characters indicate the same parts in all the views.

Let the numeral 5 designate the cast iron base and 6 the vertical side walls of the spout. These side walls are also composed of cast iron and are connected with the base by means of bolts 7 passed through registering openings formed in lateral flanges 8 of the side walls and in the outer edges of the base 5. The base projects beyond the side walls sufficiently for the purpose. Located within this cast iron shell is a lining 9 preferably composed of magnesic brick. This lining extends to the top of the cast iron side walls and covers the entire inner surface of the spout except at the front end where is located a water jacketed copper tip 10. The height of this tip is regulated according to the pressure of blast, the tip being raised high enough to give sufficient head to prevent the blast from blowing through. As shown in the drawing the tip is hollow as indicated at 12 and water is circulated therethrough by means of pipes 13. The water which enters through one of these pipes passes out through the other in the ordinary way where a water jacket is employed.

In actual practice the lining 9 will be composed of brick suitably luted together to form virtually an integral lining. In removing the tip, however, the lining bricks 85 adjacent the tip will have to be removed. In the drawing the lining 9 is shown as integral but it must be understood that it is preferable to form it of individual bricks suitably luted together as above 90 stated since in removing the tip this structure is greatly advantageous.

The rear extremity of the spout or that toward the right shown in Figs. 1 and 2 of the drawing, rests upon a bed-plate 14 of a smelting furnace (not shown). In the rear of the spout is located a tap jacket 15 through which water is circulated by means of pipes 16. This jacket is provided with an opening 17 communicating with the spout proper. The spout may be connected with the furnace in any suitable manner. As shown in the drawing this is accomplished by means of side rods 17 whose forward extremities pass through slotted lugs 18 formed on the side walls of the spout; while the opposite extremities of these rods are connected with stationary rails 19. The ex-

tremities of the rods which pass through the lugs 18 are secured in place by nuts 20.

The cast iron side walls 6 of the spout are provided at their forward extremities with 5 inwardly-projecting flanges 6^a which occupy a position in front of the tip and the lining 9. These parts are therefore supported in front by these flanges.

In order to remove the tip, the lining located above its extremities must of course be taken out, and after a new tip is substituted, the bricks removed are put in position and luted to the body of the lining as before.

From the foregoing description the use of 15 my improved device will be readily understood. It is connected with the discharge end of a smelting furnace and the molten mass including both the slag and the matte is drawn off from the furnace through this 20 spout. The matte which is heaviest or of greatest specific gravity is the element which produces the principal wear upon the spout and as heretofore intimated this wear is greater upon the tip where the molten mass 25 escapes than upon any other part. Hence this tip is made of copper and jacketed to permit a constant circulation of water. The cutting action is due to the chemical action of the matte which rapidly dissolves any-

thing but copper ninety nine per cent. pure, 30 and will even cut that quite rapidly at times. The tip being readily removable, is a very important feature since the magnesic lining of the body of the spout is very durable and will outwear a great many tips. 35

As heretofore stated in the ordinary construction when the tip became worn, the entire spout had to be discarded, and sometimes even a pure ninety-nine per cent. copper spout will cut through in a few days. 40

Having thus described my invention, what I claim is:

A tap spout for smelting furnaces comprising an outer casing composed of cast iron, a lining of magnesia brick, a water jacketed copper tip located in the front of the spout, a tap jacket located in the rear end of the spout and provided with cooling means, the walls of the spout being provided with lugs, and braces or rods adapted to pass 45 through the lugs and connect with the furnace, substantially as described. 50

In testimony whereof I affix my signature in presence of two witnesses.

FREDERICK DANIEL GROSS.
